TABLE

Charles Grossman, Nassau County, N.Y., assignor to Southern Container Corp., Deer Park, N.Y.

Filed Jan. 12, 1972, Ser. No. 217,419

Term of patent 14 years

Int. Cl. D6—03

U.S. Cl. D6—177

FIG. 1 is a perspective view of a table embodying my new design.

FIG. 2 is a plan view of the end thereof.

FIG. 3 is a plan view of the side thereof.

The opposite end is identical to FIG. 2 and the opposite side is identical to FIG. 3.

I claim:

The ornamental design for a table, substantially as shown and described.
